ELECTRIC CONVERTING SYSTEM

Burnice D. Bedford, Schenectady, N. Y., assignor
to General Electric Company, a corporation of
New York

Application April 30, 1937, Serial No. 139,893

5 Claims. (Cl. 175—363)

My invention relates to electric converting systems and more particularly to systems for effecting transfer of energy between circuits by means of switching apparatus and associated equipment.

In many applications where circuit interrupting means are used, it is desirable to control the currents of the associated circuits so that the circuit interrupting duty imposed is not excessive. It is advantageous to construct and arrange the associated circuits and equipment to effect a substantial reduction in the current to be interrupted. By reducing the current immediately prior to and coincidentally with the circuit interrupting operation, it has been found that the size and rating of the switching or circuit interrupting means may be considerably reduced as compared with that which would be required if the apparatus were required to interrupt the maximum currents of the associated circuit, or circuits.

For example, in electric translating circuits such as rectifying and inverting circuits employing switching or mechanical interrupting means, it is desirable from an economic standpoint to reduce as much as possible the current to be interrupted so that the switching or interrupting apparatus may be correspondingly reduced in size and rating. Moreover, it has been found that it is highly desirable to relieve the cooperating contacts of the switching means from all current establishing and interrupting functions so that the establishment of arcs at the contacts is entirely eliminated, thereby relieving the cooperating contacts of the most severe function in the cycle of operation.

It is an object of my invention to provide a new and improved electric converting system.

It is another object of my invention to provide a new and improved electric circuit.

It is a further object of my invention to provide a new and improved electric translating circuit.

It is a still further object of my invention to provide a new and improved circuit interrupting means for use in electric converting systems.

The subject matter of this application is an improvement of the subject matter described and claimed in my copending application Serial No. 113,581, filed December 1, 1936, entitled Electric circuits and assigned to the assignee of the present application.

In accordance with the illustrated embodiment of my invention, I employ a switching means operated in electrical synchronism with the volt-

age of an alternating current circuit for transmitting energy between the alternating current circuit and a direct current circuit. Saturable inductive devices are connected in series relation with the phase conductors of the alternating current circuit and the switching means for controlling the rate of change of current at the beginning and the end of the normal predetermined intervals of conduction of current from the alternating current circuit to the direct current circuit established by the cooperating contacts of the switching means. Each of the saturable inductive devices includes a main winding connected in series relation with one of the phase conductors of the alternating current circuit, and a control winding connected in series relation with a different phase conductor of the alternating current circuit for controlling the impedance of the associated main winding and for controlling the rate of change of current through the main winding at the beginning and at the end of the normal conductor intervals for that inductive device. Each of the saturable inductive devices may include an auxiliary winding for providing a commutating voltage. Electric valve means is connected in parallel with the switching means periodically to establish and interrupt the flow of current through the various associated saturable inductive devices to prevent sparking at the contacts of the switching means. The conductivity of the electric valve means is controlled so that the electric valve means conducts or interrupts current of only small value at the beginning and the end of the conducting intervals, permitting thereby the use of an electric valve means of relatively small rating compared with the amount of power which may be transmitted by the system.

For a better understanding of my invention, reference may be had to the following description taken in connection with the accompanying drawing, and its scope will be pointed out in the appended claims. Fig. 1 diagrammatically illustrates an embodiment of my invention as applied to an electric converting system for transmitting energy between a three phase alternating current circuit and a direct current circuit, and Figs. 2a to 2e, inclusive, diagrammatically show an arrangement of one part of the switching means, while Fig. 3 represents certain operating characteristics of the arrangement shown in Fig. 1.

In Fig. 1 of the accompanying drawing, I have diagrammatically shown my invention as applied to an arrangement for transmitting energy between a direct current circuit and an alternat-

ing current circuit comprising phase conductors 2, 3 and 4 through switching devices 5 and 6 and through a plurality of saturable inductive devices 7, 8, and 9. Each of the saturable inductive devices 7, 8 and 9 includes a saturable magnetic core member 10, a main winding 11 connected in series relation with one of the phase conductors of the alternating current circuit, a control winding 12 connected in series relation with a different phase conductor for controlling the saturation of the core member 10 and hence for controlling the impedance of the associated main winding 11, and an auxiliary winding 13 for providing a commutating voltage, the function of which will be explained hereinafter.

The switching means 5 and 6 include rotatable drum members 14 which are driven in electrical synchronism with the voltage of the alternating current circuit by any suitable means such as an alternating current motor 15 of the synchronous type having armature windings 16 and a field winding 17. The angular displacement of the drums 14 relative to the voltage of the alternating current circuit may be adjusted by any suitable arrangement such as a rotary phase shifter 18. In order to control an electrical condition of one of the associated circuits, such as the voltage of the direct current circuit 1, the angular displacement of the drums 14 may be automatically controlled in accordance with an electrical condition of one of the associated circuits, such as the current of the direct current circuit 1, by any conventional arrangement 19 which may comprise a current responsive actuating coil 20, a spring biased plunger 21 for controlling the relative angular displacement by means of a phase shifting device 22 of the rotary type. The synchronous motor 15 may be energized from any suitable source of alternating current and in the arrangement shown, the motor 15 is energized from the alternating current circuit comprising phase conductors 2, 3 and 4.

Switching device 5 includes a rotating contact 23 which extends completely around the periphery of the drum 14 and a cooperating stationary contact or brush 24 which is connected to one terminal of the direct current circuit 1. In order to control the period or interval during which current is transmitted from the phase conductors of the alternating current circuit to the direct current circuit, I provide on the surface of the drum 14 of switching device 5 a contact 25, the length of which is determined by the desired electrical interval of conduction. In the particular arrangement shown in Fig. 1, the arcuate length of the contact 25 corresponds to 120 electrical degrees. The cooperating stationary contacts or brushes 26, 27 and 28 are connected to main windings 11 of different saturable inductive devices 7, 8 and 9 respectively and are spaced at equal intervals around the periphery of the drum 14. In the particular arrangement shown, the brushes 26, 27 and 28 are displaced 120 electrical degrees.

Electric valve means 29 is connected in shunt relation with the switching device 5 to periodically short circuit the switching device to effect establishment and interruption of the current flow through the associated saturable inductive devices 7, 8 and 9 and to thereby relieve the switching device 5 of this operation. The electric valve means 29 is preferably of the type employing an ionizable medium such as a gas or a vapor and includes an anode 30, a cathode 31 and a control member 32 for controlling the conductivity there-

of. The anode 30 is connected to brush 24 through a conductor 32' and the cathode 31 is connected to the switching device 5 through a contact or brush 33 which cooperates with a rotatable contact 34 mounted on the surface of the drum 14. The contact 34 extends completely around the drum 14 and is connected to control contacts 35, 36, 37 and 38. Stationary control contacts or brushes 39, 40, 41 and stationary control contacts or brushes 42, 43 and 44 cooperate with contacts 35, 37 and 36, 38, respectively. Brushes 39 and 42 are associated with auxiliary winding 13 of inductive device 7; brushes 40 and 43 are associated with auxiliary winding 13 of inductive device 8 and brushes 41 and 44 are associated with auxiliary winding 13 of inductive device 9. The various auxiliary windings 13 are connected to the electric valve 29 through the associated control brushes and control contacts to impress on the anode 30 of electric valve means 29 a commutating voltage to transfer the current from the main windings 11 to the electric valve 29 at the end of the various conducting intervals. Contacts 35 and 36 with the associated brushes serve to connect the anode-cathode circuit of electric valve means 29 to the auxiliary windings 13 in advance of the establishment of the circuit to the associated main windings. This is accomplished by positioning the contacts 35 and 36 to lead the contact 25. Electric valve 29 is rendered conductive by means of the contact 36 and the associated brushes immediately after the anode-cathode circuit of the electric valve means 29 is established by contact 35 and the associated brushes. Electric valve means 29 is maintained nonconductive by impressing on the control member 32 thereof a negative uni-directional biasing potential. Any suitable means may be employed to effect this control and I have chosen to represent the arrangement as comprising a battery 45 and a serially connected resistance 46 connected across the cathode 31 and the control member 32. A control circuit for the electric valve means 29 which cooperates with movable contacts 36 and 38 and brushes 42, 43 and 44 serves to render the electric valve means 29 conductive at the beginning and at the end of the normal conducting intervals for each of said saturable inductive devices. The control circuit may comprise any conventional arrangement such as a source of voltage for rendering the valve 29 conductive at the desired time, and in the present arrangement I have chosen a battery 47 for impressing on the control member 32 a positive voltage at times established by the position of the contacts 36 and 38 on the drum 14. A current limiting resistance 48 may be connected in series relation with the battery 47. The arrangement of the cooperating contacts of the switching device 5 of Fig. 1 may be better understood by referring to Figs. 2a-2e, inclusive. The shaded portions of these figures represent the insulating segments of the drum.

The switching device 6 is arranged similarly to that of switching device 5 with the exception of a contact 49 which is displaced 180 electrical degrees relative to the contact 25 of switching device 5. The switching devices 5 and 6 together operate as a full wave rectifier or inverter to transfer energy between the alternating current circuit and the direct current circuit. An electric valve means 50 is connected across the switching device 6 and serves to periodically establish and interrupt the current through the main windings 11 of the associated saturable

inductive devices. The control circuit for the electric valve means 28 is similar to that for electric valve means 29.

The operation of the embodiment of my invention diagrammatically shown in Fig. 1 will be explained when the system is operating to transmit energy from the alternating current circuit comprising phase conductors 2, 3 and 4 to the direct current circuit 1. Switching devices 5 and 6 will operate as a full wave controlled rectifier to transmit energy through each of the phase conductors and the associated inductive devices during both the positive and negative half cycles of voltage of the alternating current circuit. The synchronous motor 15 will be assumed to rotate in the direction indicated by the arrow in Fig. 1 and the rotary phase shifter 18 may be adjusted to effect the desired angular displacement between the voltages of the alternating current circuit and the contacts on the drums 14 of switching devices 5 and 6. Let it be assumed that at the particular instant indicated by the positions of the drums 14 of Fig. 1, the voltage of the phase conductor 4 is positive so that current will be conducted from phase conductor 4 through control winding 12 of inductive device 8, main winding 11 of inductive device 7, brush 26, contact 25, contact 23, brush 24, to the positive terminal of direct current circuit 1, through switching device 6 to main winding 11 of inductive device 8, control winding 12 of inductive device 8 and phase conductor 3. During the greater part of the conducting intervals for each of the main windings 11 of inductive devices 7, 8 and 9, the impedance of the main windings 11 will be relatively small due to the fact that the control windings 12 have effected saturation of the associated core members 10. However, at the beginning and at the end of these conducting intervals, the core members 10 will not be saturated and the impedance of the main windings 11 will be substantially greater to effect a slow rate of change of current at the beginning and at the end of the intervals of conduction. By virtue of the leading relationship of the contact 35 relative to the contact 25, the anode-cathode circuit for the electric valve means 28 will be established prior to the establishment of the main power circuit through brush 26. Moreover, since the contact 35 leads contact 25, the electric valve means 28 will be rendered conductive by energization of the control circuit to permit electric valve means 29 to establish the flow of current through main winding 11 of inductive device 7 to relieve brush 26 and the contact 25 of this circuit establishing operation and to thereby prevent sparking between the brush 26 and the contact 25 when the circuit connection is made. Of course, the transfer of current to the electric valve means 28 will be accomplished by the operation which is commonly known as phase commutation; that is, the voltage of the inductive device 7 at this particular time in the cycle of operation is such as to cause this commutation of current.

The manner in which the electric valve means 28 effects the establishment and interruption of current through the various main windings 11 may be better understood by considering the operating characteristics represented in Fig. 3. Curve A represents the voltage of phase conductor 4 and curve B represents the current conducted by main winding 11 of inductive device 7 during a specific portion of one half cycle of voltage of the alternating current circuit. By 75

the proper adjustment of the position of the rotary phase shifter 18, it is possible to control the time during each half cycle of voltage of the phase conductors 2, 3 and 4 at which the respective associated contacts are established by the switching devices 5 and 6 and to control thereby an electrical condition such as the voltage of the direct current circuit 1. Considering the events which occur prior to the time corresponding to the relative positions of the contacts shown in Fig. 1, the line a corresponds to the time when contact 35 engages brush 39. Since the electric valve means 28 is not conductive at this time, no current will be transmitted through main winding 11. At a later time corresponding to the position of line b, contact 35 engages brush 42 to render electric valve means 28 conductive by means of the positive voltage impressed on control member 32 thereof by battery 41. During the interval b-c, the electric valve means 28 completes the circuit through the main winding 11 and auxiliary winding 13 and conducts current during the corresponding interval. At time c, movable contact 25 engages brush 26 to connect main winding 11 directly through contacts 25 and 23 and brush 24 to the direct current circuit 1. By virtue of the lower resistance of this path relative to the resistance of the path including the electric valve means 28, current will be commutated from the electric valve means 28 to the path including the main contact 25 and the associated brush 26. At time d, the impedance of the main winding 11 becomes substantially less due to the saturation of the core member 10 and the current will now increase to a substantially greater value.

The circuits to electric valve 29 controlled by contacts 35 and 36 and brushes 39 and 42 are interrupted at some time after the time c. At 40 about the time e the current conducted by main winding 11 of inductive device 7 begins to decrease due to the build-up of current in the next succeeding phase in the order of phase rotation. At time f inductive device 8 becomes saturated permitting a rapid rise in the current in main winding 11 thereof. At time g, the contact 37 engages brush 39 to establish the anode-cathode circuit of electric valve means 29. And at time h, contact 38 engages brush 42 to render electric valve means 29 conductive. The current is commutated from main contact 25 and brush 26 to electric valve means 29 at time h due to the commutating voltage provided by auxiliary winding 13 of inductive device 7. Within the 53 interval h-j, the contact 25 and brush 26 are disengaged without being required to interrupt current. And at time k the circuits to electric valve means 29, controlled by contacts 37 and 38 and brushes 39 and 42, are opened. The dotted curve C represents the current conducted by main winding 11 of inductive device 8. It is to be noted that the switching device 5, more particularly contact 25 and brush 26, conduct current during the interval c-h and that as 60 concerns phase conductor 4, the electric valve means 28 conducts current during the interval b-c as represented by curve D and that electric valve means 29 also conducts current during the interval h-j as represented by curve E. It is to be understood that the electric valve means 29 also conducts current in a similar manner for phase conductors 2 and 3; that is, it serves to establish the current and interrupt the current conducted by main windings 11 of inductive devices 8 and 9 and the associated main contact 25

and brushes 27 and 28. Electric valve means 29 and electric valve means 50 each conduct current six times during each cycle of the alternating voltage of the alternating current circuit including phase conductors 2, 3 and 4.

The relative rates at which the current increases and decreases at the beginning and at the end of the normal conducting intervals may be adjusted by the design of the saturable inductive devices 7, 8 and 9. More particularly, the rate of rise of current through the main windings 11 at the beginning of the conducting intervals may be decreased by decreasing the number of turns of the control windings 12 relative to the main windings 11. Furthermore, by decreasing the number of turns of control windings 12 relative to the main windings 11, the rate of change of current at the end of the conducting intervals will be increased.

One of the principal advantages of my invention is the arrangement whereby the switching means associated with an electric converting system is relieved of the functions of establishing and interrupting the current through the various inductive devices 7, 8 and 9. Because of this feature, the cooperating main or power contacts of the switching devices 5 and 6 are not required to establish or interrupt currents and are, therefore, not subject to the deterioration incident to apparatus performing these functions and may be materially reduced in size and rating relative to the amount of energy which can be transmitted and controlled by the system.

Controlling means 19 automatically controls the angular position of the synchronously driven switching devices 5 and 6 with respect to the voltage of the alternating current circuit to control the voltage of direct current circuit 1 in accordance with the current of the direct current circuit or in accordance with the amount of power transmitted between the alternating current circuit and the direct current circuit. This arrangement automatically controls the time of transfer of current among the various phase conductors in accordance with a load condition of one of the circuits.

While I have shown and described my invention as applied to a particular system of connections and as embodying various devices diagrammatically shown, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States is:

1. In combination, an alternating current circuit including a plurality of phase conductors, a direct current circuit, switching means for selectively connecting said phase conductors to said direct current circuit, a plurality of saturable inductive devices each associated with a different one of said phase conductors and each including a core member, a main winding connected in series relation with a predetermined one of said phase conductors, a control winding connected in series relation with a predetermined different one of said phase conductors for controlling the inductance of the associated main winding and an auxiliary winding, and electric valve means for periodically short circuiting said switching means to establish and interrupt the current through said main winding, said auxiliary wind-

ing providing the commutating voltage to effect transfer of current from said switching means to said electric valve means immediately preceding the end of the normal intervals of conduction by said main winding.

2. In combination, an alternating current circuit comprising a plurality of phase conductors, a direct current circuit, a plurality of saturable inductive devices each associated with a different one of said phase conductors and each comprising a core member, a main winding connected in series relation with one of said phase conductors, a winding connected in series relation with a different phase conductor for controlling the inductance of said associated main winding and an auxiliary winding for producing a commutating voltage, a switching means interposed between said inductive devices and said direct current circuit for selectively connecting said inductive devices to said direct current circuit to transmit energy between said alternating current circuit and said direct current circuit through said inductive devices during different predetermined intervals, and electric valve means connected in shunt relation with said switching means and connected with said auxiliary winding for establishing and interrupting the flow of current through said inductive devices.

3. In combination, an alternating current circuit comprising a plurality of phase conductors, a direct current circuit, a plurality of saturable inductive devices each associated with a different one of said phase conductors and each including a core member, a main winding connected in series relation with one of said phase conductors, a control winding for controlling the inductance of the associated main winding and an auxiliary winding, switching means interposed between said main windings and said direct current circuit for selectively connecting said main windings to said direct current circuit to effect energy transfer between said alternating current circuit and said direct current circuit and comprising a plurality of cooperating contacts each associated with a different one of said inductive devices and an electric valve means connected in shunt relation with said contacts and controlled by said auxiliary windings for establishing and interrupting the flow of current through said cooperating contacts to prevent sparking at said contacts.

4. In combination, an alternating current circuit comprising a plurality of phase conductors, a plurality of saturable inductive devices each associated with a different one of said phase conductors and each comprising a core member, a main winding connected in series relation with one of said phase conductors, a control winding connected in series relation with a different one of said phase conductors for controlling the magnitude and the rate of change of current through the associated main winding at the beginning and the end of the normal conducting intervals therefor and an auxiliary winding for providing a commutating voltage, switching means interposed between said inductive devices and said direct current circuit and comprising a plurality of cooperating contacts each associated with a different one of said main windings for effecting current transfer between said alternating current circuit and said direct current circuit during predetermined intervals, an electric valve means connected across said switching means and connected to be controlled by said auxiliary windings, and a control circuit for said electric valve means for rendering said electric valve

means conductive to establish and interrupt the flow of current through said main windings.

5. In combination, an alternating current circuit comprising a plurality of phase conductors, a direct current circuit, a switching means operated in electrical synchronism with the voltage of said alternating current circuit for effecting transfer of energy between said alternating current circuit and said direct current circuit and comprising a plurality of cooperating main contacts and a plurality of cooperating control contacts, a plurality of saturable inductive devices interposed between said alternating current circuit and said switching device and each comprising a core member, a main winding connected in 15 series relation with a predetermined different

phase conductor, a control winding connected in series relation with another phase conductor for controlling the magnitude and the rate of change of current through the associated main winding at the beginning and at the end of the normal conducting intervals and an auxiliary winding for providing a commutating voltage, an electric valve means connected across said main contacts of said switching device to establish and interrupt the flow of current through said main windings, and a circuit for said electric valve means controlled by said control contacts for controlling the conductivity of said electric valve means.

BURNICE D. BEDFORD.
